UNITED STATES PATENT OFFICE.

CHARLES ANDRÉ COPPIER, OF PARIS, FRANCE.

PROCESS OF TREATING FIDUCIARY PAPERS FOR THE PURPOSE OF PREVENTING FRAUD.

1,271,857.

Specification of Letters Patent.

Patented July 9, 1918.

Application filed January 20, 1915. Serial No. 3,299.

To all whom it may concern:

Be it known that I, CHARLES ANDRÉ COPPIER, of 1 Rue de Pontoise, Paris, France, engraver, have invented a new and useful 5 Improvement in Processes of Treating Fiduciary Papers for the Purpose of Preventing Fraud, which improvement is fully set forth in the following specification.

It is known that important papers are very 10 easily falsified and that criminal frauds are committed which consist mainly—

(1) In forging or altering bank notes, bills, stamps, trade marks, etc.

(2) In scratching or washing out the 15 numbering or names after theft,

(3) In altering the value of a check, etc.

Such frauds are facilitated by the elementary processes at present employed in the preparation of documents.

20 Most indeed are printed or typographically printed in two or three shades on paper watermarked in the pulp. In this manner dull tints of the same color, shade and intensity are obtained which it is easy 25 to reproduce by photomechanical processes or in other known ways.

When the foundation for the subsequent printing or writing consists in combinations of letters or small ornamental designs repeated in series in such a manner as to produce a tint which is usually light blue it forms only an illusory guarantee, for with a little trouble it is easy to copy a fragment comprising the complete series of the letters

35 or ornaments and thus be enabled to repeat it indefinitely.

If therefore a number or writing upon such special foundation is erased or washed out it will be easy to reprint the foundation 40 where erased or washed out and then write a new text or other number.

A watermark in the pulp can also be produced by anyone who knows how to draw a monogram with copper wires or model a 45 figure in relief, then using linen and paper pulp which is easily procurable. A watermark may moreover be forged easily by erasure or by a normal impression with the aid of an original matrix copied upon the 50 model of the original document.

Moreover, watermarks made with the paper have a soft and colorless appearance and may substantially vary in size or be deformed on account of the subsequent drying

of the paper; vignettes for this reason can 55 never tally with precision in the prints.

Many notes or documents are, however, printed by copper plates but are made and executed by semi mechanical and commercial engraving with foundations such as 60 obtained in Russian notes or by other processes which offer premiums on forgery.

This invention has for its object to provide a process for treating paper suitable for documents of all kinds and shapes such as 65 checks, stamps, titles, coupons, trade marks, bank notes, railway tickets, certificates of ownership of stocks, diplomas, etc., in such a manner as to render it impossible to forge such documents without the aid of original 70 parts or the machine pieces which have been used to prepare them. The paper cannot be successfully photographed owing to the special gray shades which are obtained without the employment of colors, oil, par- 75 affin, petrol, wax, etc.

Paper treated according to this process has a peculiar and novel appearance on the surface, in the body of the paper itself, in its opaqueness or transparency, and in the 80 brilliant mat or semi mat appearance of its surfaces (whether paper already transparent or opaque be employed); these surfaces may be modified on both sides at once or on one side only; the whole surface may be modified or a portion only of the surface and in shapes or figures which may vary indefinitely.

The appearance of the prints, whether copper plate, letter press or color printed, 90 etc., and the appearance of the outer surfaces of the paper (or of the inner surfaces in the case of an impression sunk unto the body of the paper) can both be altered as desired.

By this process impressions which are visible without holding the paper to the light and of extreme fineness in details may be produced before, during or after printing and in the body of the paper.

The impressions may be isolated in the harmony of the printed document with the image plainly visible on the special gray shade produced in the process as above mentioned.

As printing takes place in the dry and cold the impressions can be placed accurately as regards any other printed matter

produced with greasy ink by copper plate, letter press or lithography, etc.

The impressions may play a part in letter press and copper plate printing or other processes by producing a tone impossible to obtain by the usual processes and this may be carried out on both sides of the paper at once which, however, loses none of its qualities of resistance or lasting. They 10 may be impressed simultaneously upon both surfaces of the paper and thus increase the variety of effects.

The process which forms the subject of 15 this invention consists in impressing paper by lamination, striking in a stamping press, or in any other manner after having interposed on one or both surfaces of the paper matrices of metal or other hard substance modeled and chased or engraved after the 20 model or other object to be obtained.

These matrices may be made by any of 25 the direct mechanical or photomechanical processes at present in use for cutting metal or wood.

In place of matrices there may be 30 employed stencils of paper, metal or gelatin, etc., which are placed in layers, each layer having first been subjected to uniform pressure. This process effects the combination 35 of copper plate or like printing without ink and medal striking with special models of the medals reduced to the least possible thickness.

The paper subjected to impression between a matrix and a flat base or between 40 two matrices whose hollows or projections may or may not coincide has a glossy transparent appearance in the compressed parts similar to vegetable tracing paper, an 45 appearance whose transparency becomes greater or less in the parts more or less compressed and preserves its original appearance in the remaining parts of the matrix or stencil. The image, object or filigram it is desired to reproduce is obtained in a 50 whole gamut of tones starting from a gray tone transparent in the parts most compressed to the tone of ordinary paper in the uncomplicated parts.

The production of this novel form of 55 impression upon paper already watermarked in the body of the paper increases still further the difficulties of imitation.

The accompanying drawing illustrates the invention.

The chosen example illustrates the treatment of paper which is supposed to be 60 printed on both the obverse and the reverse side. Figure 1 shows the result of an impression on white paper of the matrix prepared for the obverse side and having numbers in the four corners thereof obtained by mechanical numbering. Fig. 2 shows the result of a similar impression on 65 white paper prepared for the reverse side,

the shaded portions, here as in Fig. 1, representing the parts made transparent or translucent by the impression. Figs. 3 and 4 show respectively the obverse and reverse side of the paper to be treated, the vignette 70 being printed with colored ink. Figs. 5 and 6 show respectively the obverse and reverse side of the paper of Figs. 3 and 4 after treatment by the matrices whose impressions are individually illustrated in Figs. 1 75 and 2. Fig. 7 is an enlarged cross section on line A—B of Fig. 1. This treatment produces more or less gray or transparent tones which are directly visible on the obverse and the reverse portion of the paper. 80

If the paper has been printed in one or more colors at the obverse and the reverse these colors will coact either alone with the tint of the image or impression obtained by compression or together with the colors on the other side of the sheet, but transformed by the remaining thickness of the paper according as this remains opaque or becomes transparent. Thus, in the example illustrated, if one side of the paper be printed 90 in red ink and the other in blue ink, some of the red effect appears in the resultant blue design, while some of the blue effect appears in the resultant red design.

In order to obtain extremely fine impressions matrices engraved and chased for this purpose are employed.

It will easily be understood that it is impossible to imitate papers without the aid of the original matrix or to reproduce them 100 by the usual photomechanical processes owing to this transparency of the paper which allows the image printed on the other side of the paper to appear simultaneously in places only.

In order to insure the greatest security to the issuers and possessors of fiduciary papers the process may be combined with the following operations:

(1) The impression of the paper may be 110 employed jointly with copper plate or similar printing whereby the texture of the print will be modified because the ink in the deep and large cuts will be expelled at the compressed parts while the sharp appearance and relief of the copper plate print is maintained. In the half tints the impression causes a supplementary edge impossible to photograph alone but will again modify in selected places the tone and texture of the 120 half tones which will thus be rendered impossible of photographing and reproduction.

In the white unprinted portions, this impression may cause a whole gamut of tones 125 and appearances in relief and depth inimitable without the original matrices and incapable of being photographed as has been explained above.

A single copper plate printing at the back 130

and the obverse of the paper combined with an impress printing can produce nine different color tones without taking note of the shades of these tones, or the variable appearance of the three combinations.

(2) This process may be combined with watermarking in the paper pulp, above which is printed an impress which will modify the original appearance of the first 10 watermark in such a manner as to prevent reproduction.

(3) In letter press printing an impression of this sort causes the first impression to be altered by difference in the coloration 15 of the impress and allows a second impression upon the relief thus produced in the paper to be effected.

(4) The same arrangement may be employed with polychromatic lithographic printing in algraphy in the Rembrandt 20 process, etc.

(5) Impressing by compression allows the use of movable figures or signs which are interchangeable or can be displaced axially 25 and this may form a secret means of control.

(6) The impression may thus form the ground of different shades upon paper colored in the pulp and which receives at the surface an impression of covering color 30 above an impression with transparent inks.

(7) In the case of deep impressions, or those introduced into the body of the paper, the impression may cause the image invisible beneath the opaque paste of the paper 35 to become visible more or less at the surface of the paper.

This process may also be employed with all types of paper marks with images of all kinds, portraits, etc.

40 Claims—

1. The process of treating fiduciary papers which comprises compressing the papers while dry with the interposition of a matrix having elevations of varying height to produce 45 varyingly-translucent portions over the impressed area.

2. The process of treating fiduciary papers which comprises compressing the papers between opposed matrices having elevations 50 of varying height to produce over the impressed area varyingly-translucent portions partaking of the combined effects of both matrices.

3. The process of treating fiduciary papers which comprises printing thereon with colored ink, and compressing the printed papers with the interposition of a matrix having elevations of varying height to produce over the impressed area varyingly-translucent portions modified by the color effects of 55 said ink.

4. The process of treating fiduciary papers which comprises printing on the opposite sides thereof with colored ink, and compressing the printed papers between matrices 65 having elevations of different height to produce over the impressed area varyingly-translucent portions partaking of the combined effects of both matrices and modified by the color effects of said ink. 70

5. The process of treating fiduciary papers which comprises printing on the opposite sides thereof with inks of different color, and compressing the printed papers between matrices having elevations of different 75 height to produce over the impressed area varyingly-translucent portions partaking of the combined effects of both matrices and modified on each side by the color effects on the opposite side. 80

6. The process of treating fiduciary papers which comprises giving the papers an initial watermark, and compressing the papers with the interposition of a matrix or matrices having elevations of different height to produce over the impressed area varyingly-translucent portions modified by the initial 85 watermark.

7. The process of treating fiduciary papers which comprises giving the papers an initial 90 watermark, printing on one or both sides thereof with colored ink, and compressing the papers with the interposition of a matrix or matrices having elevations of different height to produce over the impressed area varyingly-translucent portions modified by 95 the initial watermark and the color effects of said ink.

In testimony whereof I have signed this specification in the presence of two subscribing witnesses.
